APPAREL

Benjamin Liebowitz, New York, N. Y., assignor to
 Trubenizing Process Corporation, New York,
 N. Y., a corporation of New York

Application April 5, 1932, Serial No. 603,242

11 Claims. (Cl. 2—131)

This invention relates to articles of wearing apparel.

It is an object of the invention to provide a porous moisture permeable stiffened or partly stiffened article of wearing apparel, which is of such character that it may be laundered repeatedly without deleteriously affecting its stiffening properties.

A further object of this invention is to provide simple, practical and efficient means for binding together a plurality of plies of fabric in the course of manufacture of an article of wearing apparel such as a collar, cuff, or the like.

The invention is particularly suitable for use in the production of stiffened collars of the semi-soft or soft roll type. In such use it gives the collar a stiffened appearance without necessity of starching, and, inasmuch as the stiffener is pervious both to air and moisture, its use will not render the collar less comfortable to wear or more difficult to launder.

While in the following description and accompanying drawings I shall describe and illustrate the invention in relation to its use for stiffening collars, it is to be understood that it may be used for other purposes and that modifications may be made therein without departing from the spirit or scope of the invention.

Generally stated, the invention comprises the use of an arrangement of threads of cellulose ester as a stiffening medium and binder for uniting two or more plies of textile fabric.

I am aware that prior to my invention it has been proposed to stiffen fabrics for use in making collars and other articles of apparel by treating the fabrics with a stiffening agent composed of a solution of cellulose ester such as nitrocellulose, or esters of the higher acetates, for example: pyroxylene or celluloid compositions.

Such treatment, while it results in stiffening the fabric, has the disadvantage that it renders the fabric impervious to moisture. In order that the fabric may be easily and thoroughly washed as well as smoothly ironed, it is desirable that the stiffener be so arranged as not to make the fabric impervious to water.

According to my invention, I attain this purpose by stiffening the fabric with artificial threads employing cellulose as a base or initial basic material, such as celanese, acetate or the like. A distinguishing feature of the invention is that the threads are spaced apart, relatively to their thickness or diameter, sufficiently to prevent them from filming over, and thus filling or closing the spaces,

when the threads are peptized or treated with a solvent.

In the accompanying drawings:

Figure 1 is a plan view of a loosely woven fabric or network of cellulose ester threads; 60

Fig. 2 is a view showing the cellulose ester fabric inserted between two plies of textile fabric; 65

Figs. 3 and 4 represent embodiments of the invention applied to collars having an interlining between the stiffener and the outer ply of the 65 collar;

Figs. 5 and 6 illustrate applications of the invention to collars in which the interlining between the stiffener and the outer ply of the collar is omitted. 70

The stiffening material, in the form shown in Figure 1, comprises a network of threads 10 of cellulose ester, such as a woven fabric comprising yarns or threads of celanese, acetate, or the like.

11 and 12 represent two layers or plies of textile 75 fabric between which the woven fabric or network 10 of cellulose ester threads is placed. The assembly is then stiffened and bound together by moistening with acetone or other suitable solvent which will peptize the cellulose ester threads. A 80 preferred method of doing this is to place the plies between two pads wet with the solvent and applying pressure. Heat and further pressure is then applied, as a result of which the solvent is driven off. The cellulose ester remains behind 85 no longer as a fabric, but as a checkered structure, partly dispersed into the adjoining fabric plies, which checkered structure adhesively binds the plies together and stiffens them. It is to be noted that in the practice of my invention the 90 adhesive binder does not form a continuous film but has open spaces which make the laminated fabric pervious both to air and water.

In the embodiment of the invention shown in Fig. 3 the collar has an outer ply 13, an interlining 14, lying next to the outer ply and extending the full length of the collar, a loosely woven fabric or network 15 of celanese or the like, and an inner ply 16. In this instance, the celanese does not extend completely around the collar but only the 100 points are stiffened, although it is to be understood that if desired the entire collar may be stiffened.

Fig. 4 shows a modification in which a second layer 17 of loosely woven fabric of celanese is 105 employed and an additional interlining 18 is applied between the two layers of celanese 15 and 17. Instead of having the celanese fabric 15 and 17 and the lining 18 of separate parts, they may be interwoven in one piece with the celanese threads. 110

In the forms of the invention shown in Figs. 5 and 6, the interlining 14 is omitted and the celanese is applied directly against the outer ply of the collar. In this use it is desirable to employ a finer weave so that the celanese structure will not show on the outside surface of the collar, as is the case when a celanese fabric of very coarse weave is used without an interlining between the celanese and the outer ply.

10 In connection with the forms of collar shown in Figs. 3 and 4, I have found that good results are obtained by using a celanese fabric formed of multiple ply threads totaling from 200 to 300 denier and counting approximately 12 meshes per inch in the warp and/or the filler. In the forms shown in Figs. 5 and 6, I have obtained good results by using celanese fabric composed of threads measuring 45 or 50 denier and counting about 35 to the inch in the warp and/or filler.

20 One of the important advantages of my invention lies in the fact that the collar or other article of apparel can be fabricated by usual methods and the stiffening treatment applied after the stitching operations are completed. As, for example, 25 in the collars illustrated, the several parts are first sewn together and then turned inside out, as usual, whereupon the plies are again stitched along the lines 19.

The material is then stiffened as hereinbefore 30 described which stiffening operation may be performed either prior or subsequent to forming the stitches 19. It will be obvious that if a pre-stiffened material were used, the operation of turning the collar inside out would be difficult, 35 and perhaps impractical.

In the form of the invention shown in Figs. 5 and 6, all of the plies which comprise the collar are adhesively bound together, so as to form, in effect, a one-ply collar somewhat like a starched 40 collar, but with the advantage that the adhesive binding and stiffening remains substantially unaltered after repeated washings except that during the first washing a small decrease in stiffening may result due, mainly, to the dissolving of 45 ingredients in the unwashed fabrics themselves.

The binder is of such character as permanently to stiffen the article to which it is applied or in which it is used, as to be substantially insoluble in water or ordinary laundering reagents, as not 50 to be softened materially when wet with water, and as to be substantially unaffected by ordinary laundering or ironing temperatures. While I have described my invention as carried out by means of commercially available cellulose acetate 55 fabrics such as celanese or acetate, it is to be understood that binding materials of other physical and chemical composition may be employed.

What I claim is:—

1. A moisture permeable stiffened article of 60 apparel comprising two or more plies of textile fabric having their opposed faces adhesively united with a binder of cellulose derivative threads in open mesh arrangement.

2. A moisture permeable stiffened article of 65 apparel comprising two or more plies of textile

fabric having their opposed faces adhesively united with a binder comprising a plurality of cellulose derivative threads, said threads being spaced relatively to each other a distance greater than the thickness or diameter of each thread.

3. A moisture permeable stiffened article of apparel comprising two or more plies of textile fabric having their opposed faces adhesively united with a binder of cellulose derivative elements arranged to provide open spaces between said elements.

4. A semi-soft collar comprising an outer ply, an inner ply, and an intermediate adhesive stiffening layer comprising cellulose derivative threads disposed in intersticed arrangement.

5. A semi-soft collar comprising an outer ply, an interlining, an inner ply, and an adhesive stiffening layer of cellulose derivative threads between the interlining and the inner ply, said cellulose derivative threads being disposed in intersticed arrangement.

6. A semi-soft collar comprising an outer ply, an inner ply, and an adhesive stiffening layer interposed between said plies, said adhesive stiffening layer comprising textile lining material 100 having cellulose ester threads in the form of an open mesh on both faces of the lining material.

7. The method of making a stiffened article of apparel which comprises applying a fabric comprising cellulose derivative threads between the opposed faces of two plies of textile fabric, treating the laminated fabric with a solvent adapted to 105 peptize the cellulose derivative threads, and applying pressure and heat to unite and stiffen the plies.

8. The method of making a stiffened article of apparel which comprises applying an open mesh fabric of cellulose ester threads between the opposed faces of two plies of textile fabric, treating the laminated fabric with a solvent adapted to 115 peptize the cellulose ester threads, and applying pressure and heat to unite and stiffen the plies, the threads of the cellulose ester fabric being so spaced that when peptized interstices will be left between the threads.

9. The method of making a semi-soft collar which consists in forming a complete collar comprising outer and inner plies of textile fabric and an intermediate ply comprising cellulose derivative threads, wetting complete collar with a solvent which will peptize the cellulose derivative 125 threads, and applying heat and pressure to unite and stiffen the plies.

10. An article of apparel comprising plies of textile fabric united by a discontinuous adhesive 130 layer, the discontinuities whereof are spaced sufficiently closely so that their pattern will not be apparent on the surface of the article.

11. A garment part comprising plies of textile fabric united by an adhesive layer having inter- 135 stices which are spaced sufficiently closely so that the pattern of said interstices will not be apparent on the surface of the article.

BENJAMIN LIEBOWITZ. 140

DISCLAIMER

1,968,409.—*Benjamin Liebowitz*, New York, N. Y. APPAREL. Patent dated July 31, 1934. Disclaimer filed May 17, 1939, by the assignee, *Celanese Corporation of America*.

Hereby enters this disclaimer to claims 2, 3, 4, 7, 9, 10, and 11 of said specification.
[Official Gazette June 13, 1939.]

In the forms of the invention shown in Figs. 5 and 6, the interlining 14 is omitted and the celanese is applied directly against the outer ply of the collar. In this use it is desirable to employ a finer weave so that the celanese structure will not show on the outside surface of the collar, as is the case when a celanese fabric of very coarse weave is used without an interlining between the celanese and the outer ply.

10 In connection with the forms of collar shown in Figs. 3 and 4, I have found that good results are obtained by using a celanese fabric formed of multiple ply threads totaling from 200 to 300 denier and counting approximately 12 meshes per inch in the warp and/or the filler. In the forms shown in Figs. 5 and 6, I have obtained good results by using celanese fabric composed of threads measuring 45 or 50 denier and counting about 35 to the inch in the warp and/or filler.

20 One of the important advantages of my invention lies in the fact that the collar or other article of apparel can be fabricated by usual methods and the stiffening treatment applied after the stitching operations are completed. As, for example, 25 in the collars illustrated, the several parts are first sewn together and then turned inside out, as usual, whereupon the plies are again stitched along the lines 19.

The material is then stiffened as hereinbefore 30 described which stiffening operation may be performed either prior or subsequent to forming the stitches 19. It will be obvious that if a pre-stiffened material were used, the operation of turning the collar inside out would be difficult, 35 and perhaps impractical.

In the form of the invention shown in Figs. 5 and 6, all of the plies which comprise the collar are adhesively bound together, so as to form, in effect, a one-ply collar somewhat like a starched 40 collar, but with the advantage that the adhesive binding and stiffening remains substantially unaltered after repeated washings except that during the first washing a small decrease in stiffening may result due, mainly, to the dissolving of 45 ingredients in the unwashed fabrics themselves.

The binder is of such character as permanently to stiffen the article to which it is applied or in which it is used, as to be substantially insoluble in water or ordinary laundering reagents, as not 50 to be softened materially when wet with water, and as to be substantially unaffected by ordinary laundering or ironing temperatures. While I have described my invention as carried out by means of commercially available cellulose acetate 55 fabrics such as celanese or acetate, it is to be understood that binding materials of other physical and chemical composition may be employed.

What I claim is:—

1. A moisture permeable stiffened article of 60 apparel comprising two or more plies of textile fabric having their opposed faces adhesively united with a binder of cellulose derivative threads in open mesh arrangement.

2. A moisture permeable stiffened article of 65 apparel comprising two or more plies of textile

fabric having their opposed faces adhesively united with a binder comprising a plurality of cellulose derivative threads, said threads being spaced relatively to each other a distance greater than the thickness or diameter of each thread.

80

3. A moisture permeable stiffened article of apparel comprising two or more plies of textile fabric having their opposed faces adhesively united with a binder of cellulose derivative elements arranged to provide open spaces between said elements.

85

4. A semi-soft collar comprising an outer ply, an inner ply, and an intermediate adhesive stiffening layer comprising cellulose derivative threads disposed in intersticed arrangement.

90

5. A semi-soft collar comprising an outer ply, an interlining, an inner ply, and an adhesive stiffening layer of cellulose derivative threads between the interlining and the inner ply, said cellulose derivative threads being disposed in intersticed arrangement.

95

6. A semi-soft collar comprising an outer ply, an inner ply, and an adhesive stiffening layer interposed between said plies, said adhesive stiffening layer comprising textile lining material 100 having cellulose ester threads in the form of an open mesh on both faces of the lining material.

7. The method of making a stiffened article of apparel which comprises applying a fabric comprising cellulose derivative threads between the opposed faces of two plies of textile fabric, treating the laminated fabric with a solvent adapted to 105 peptize the cellulose derivative threads, and applying pressure and heat to unite and stiffen the plies.

8. The method of making a stiffened article of apparel which comprises applying an open mesh fabric of cellulose ester threads between the opposed faces of two plies of textile fabric, treating the laminated fabric with a solvent adapted to 115 peptize the cellulose ester threads, and applying pressure and heat to unite and stiffen the plies, the threads of the cellulose ester fabric being so spaced that when peptized interstices will be left between the threads.

9. The method of making a semi-soft collar which consists in forming a complete collar comprising outer and inner plies of textile fabric and an intermediate ply comprising cellulose derivative threads, wetting complete collar with a solvent which will peptize the cellulose derivative threads, and applying heat and pressure to unite and stiffen the plies.

10. An article of apparel comprising plies of textile fabric united by a discontinuous adhesive 120 layer, the discontinuities whereof are spaced sufficiently closely so that their pattern will not be apparent on the surface of the article.

11. A garment part comprising plies of textile fabric united by an adhesive layer having inter- 125 stices which are spaced sufficiently closely so that the pattern of said interstices will not be apparent on the surface of the article.
